HOLDER FOR MATCH PACKAGES

Kurt Landauer, Stuttgart, Germany

Application August 2, 1934, Serial No. 738,147
In Germany June 2, 1934

2 Claims. (Cl. 206—20)

The invention relates to holders for match packages of the kind commonly known as pull-match packages, as they leave portions of the match stalks exposed, enabling the matches to be removed singly by pulling. My invention is principally concerned with match packages of this kind having ignition surfaces on which the match heads are rubbed by the act of pulling the matches out of the packages, so that ignition of the match 5 is effected simultaneously with its removal from the package.

According to my invention a holder for such match packages is made by providing a stand or bracket with a seat adapted to engage an outwardly projecting flange of the package. Preferably the seat is annular and constructed to support the package with the matches in position for removal by downward pull.

Holders supporting match packages in this 20 position have heretofore been proposed, but are furnished with screws or the like for fixing the match packages to them. In my invention no fastening device for the package is required.

An embodiment of the invention is shown in 25 the annexed drawing, partly in section.

The match package consists of a spirally coiled strip 1 of cardboard or the like having the matches 2 housed in the spaces between its coils, with large portions of the match stalks projecting, but 30 with the match heads 2¹ inside so that on withdrawal of a match the same is ignited by friction with an ignition surface provided for that purpose on the strip 1. The spiral formed by the strip 1 is glued to a disk 3 of cardboard or 35 the like of such size that its rim portion forms a flange 3¹ at the circumference of the package.

The holder is a broad ring 4, of about the same width as the strip 1, carried by a bracket 5, the foot of which is fixed to the center of an ash-tray 6. The bracket may be duplicated, as indicated by broken lines at 5¹.

The match package is dropped into the ring from above, so that the flange 3¹ comes to rest on the seat formed by the top edge of the ring 4. 40 The matches can then be removed singly by pull-

ing them downwards, the package being retained by the ring 4.

It will be understood that the ring 4 may be fixed to any convenient support. It may, for example, be fixed to a support or bracket projecting from a wall, instead of to a bracket with a foot standing on the table.

Instead of forming a complete ring the seat may consist of segments of a ring, with gaps between them. Of course the seat may be of other 10 than annular shape, for supporting packages which are not cylindrical.

It is generally desirable to make the package fit fairly tightly into the ring 4, so as to give it additional hold by friction.

A cap 7 may be provided, fitting over the ring 4 and enabling the disk 3 to be concealed. The cap has a slot 7¹ at its rim, so that it does not foul the bracket.

Instead of a cap which simply slips on to the 20 holder I may use one which is fastened to the holder, as by screwing it on, or by means of a bayonet joint or the like.

What I claim as my invention and desire to 25 secure by Letters Patent of the United States is:—

1. The combination of a pull-match package having a flange at the rim thereof, and a holder for said package consisting of a stand and a horizontal frame projecting from said stand, embracing said package and forming a seat on which 30 said flange rests, the matches projecting downwards from said package for removal by downward pull.

2. The combination of a pull-match package having a flange at the rim thereof, and a holder 35 for said package consisting of a stand and a horizontal frame projecting from said stand, embracing said package and forming a seat on which said flange rests, the matches projecting downwards from said package for removal by downward pull said stand consisting of an ash-tray and a bracket rising from said ash-tray, supporting 40 said frame over said tray.
